ICE CREAM CUTTER AND SERVER

Ray E. Rothenbush, Los Angeles, Calif., assignor
of one-half to Bertha Druding, Beech Grove,
Ind.

Application April 21, 1939, Serial No. 269,094

11 Claims. (Cl. 107—48)

This invention relates to means for dipping ice cream in relatively fixed quantities from a bulk container and has for a primary object the cutting and serving of ice cream to be uniform in 5 shape and size. A further object of the invention is to provide a tool that will actually surround and engage the cut-away serving of ice cream so that it may be lifted bodily and safely out of the bulk can and deposited in a cone or dish as 10 desired.

A further object of the invention is to provide means to release the serving of cream from the dipper at the desired time so that the serving will discharge freely and cleanly therefrom.

15 A further important advantage of the invention is that by reason of the unique combination of elements hereinafter set forth particularly in the claims, the device may be manufactured at a relatively low cost and also will be easily cleaned 20 without having to take it apart. There is also the advantage of having the entire mechanism so assembled that it may be operated in a natural manner by the gripping of the operator's hand so that his other hand is free to hold a dish or 25 cone to receive the serving.

These and many other objects and advantages 30 of the invention will become apparent to those versed in the art in the following description of one particular form of the invention as illustrated in the accompanying drawing, in which

Fig. 1 is a side view in partial section;

Fig. 2, an end elevation;

Fig. 3, a transverse section on the line 3—3 in Fig. 2; and

Fig. 4, a transverse section on the line 4—4 in Fig. 2.

Like characters of reference indicate like parts throughout the several views in the drawing.

40 I form a housing 10 in any suitable manner such as by die casting. The upper portion of this housing 10 is curved around in the nature of a pistol grip and is made hollow with a slot through the underside of the wall to receive slidably therethrough a finger piece 11. The housing 10 has a transverse wall 12 against which the lower end of the piece 11 normally rests.

45 A shaft 13 is entered through a hole in this wall 12 with a running fit. This shaft 13 is provided with a spiral groove 14 to receive one or more balls 15, here shown as two in number. Each of these balls is carried in a fixed location in the foot 16 of the piece 11. In the particular form herein shown, this foot 16 is drilled to form passages 17, one each entering from the front and rear sides 50 and continuing through a central vertical bore 55

in the foot 16 to permit the formation of a semi-spherical seat on the opposite side of the bore.

The shaft 13, upon being entered through the transverse wall 12, is pushed through the bore of the foot 16 to have the spiral groove 14 engage about the first ball 15, and thereafter the shaft 13 is carried on up in a revolving manner to engage the next above ball 15 and then is carried upwardly until a head 18 on the lower end of the shaft 13 is brought into abutment with the underside of the transverse wall 12 as a limiting factor of travel.

The upper forward side of the housing 10 is formed with an opening therethrough, through which opening the upper end of the shaft 13 extends. A compression spring 19 is dropped over the upper end of the shaft 13 to have its lower end bear against the upper end of the foot 16 which extends laterally into the housing 10 from the piece 11. A housing closure 20 is formed to 20 have a bore entering therein from its underside to receive with a running fit at least the upper end of the shaft 13. This closure 20 is provided with an annular groove 21 extending into it from the bore. The shaft 13 is provided with a groove 25 22 therearound to receive a spring washer 23 therein. This washer 23 is split so that it may be compressed within the groove 22 to permit passing the closure 20 down over the upper end of the shaft 13 to that position wherein the spring 30 washer 23 will spring outwardly to engage within the closure groove 21, the washer 23 then being partially in both the shaft groove and the closure groove. The closure 20 is provided with a flange 35 24 engaging against the housing 10 and also has a portion extending through the housing wall as a guide. When the washer 23 is seated, as above indicated, the closure 20 is maintained in position against outward displacement by reason of the head 18 on the lower end of the shaft 13 abutting 40 the transverse wall 12. Downward movement of the shaft 13 is prevented through the washer 23 by reason of the flange 24 bearing against the housing 10. Incidentally the upper portion of the closure 20 is shaped to form a thumb rest. 45

The finger piece 11 has a major opening 25 through which the fingers of the operator may be passed when the tool is being inserted into the ice cream. The lower end of the housing 10 is continued downwardly below the transverse wall 50 12, as indicated in Figs. 1 and 2, to form a hollow, approximately semi-conical section opening on a diametrical plane from the rear or inner side. A cutter 26 is formed to fit closely within this lower housing portion and has an upper transverse cir- 55

cular end 27 attached to the head 18 of the shaft 13 in any suitable manner, such as by being welded thereto.

The attachment of the end 27 to the head 18 is made to position the cutter 26 normally within the homologous housing portion when the foot 16 is abutted against the wall 12 by the spring 19. The opening is provided through this end 27 to match with a bore in the lower end of the shaft 13 and a stud 28 carrying a relatively narrow, thin bar 29 is inserted through that hole and entered in the bore of the shaft 13 to have a split spring washer 30 spring outwardly from the stud into a retaining groove formed within the bore of the shaft so that the bar 29 is retained snugly against the end 27 but is free to turn thereover.

As indicated in Fig. 3, this bar 29 is relatively narrow as well as being thin and carries a down-turned fin 31 from one edge.

In using this cutter, the operator grips the housing 10 to have his thumb bear against the closure 20 and his fingers extend through the opening 25 in the piece 11 and forces the lower 25 spoon-like end of the housing down into the cream until the surface of the cream abuts the end piece 27 of the shiftable cutter. Then, holding the tool in that position, he shifts his fingers from the opening 25 to place them around the 30 underside of the piece 11, preferably in the finger positioning notches in said underside of piece 11, and squeezes that piece 11 upwardly into the cavity within the housing 10. This action causes the shaft 13 to rotate and thus turn the cutter 35 26 one hundred and eighty degrees at least to cut entirely around the cream, forming a conical piece thereby. While the piece 11 is thus retained in its upper position, the tool is lifted to carry the cut-away portion of cream and then 40 held over the receptacle as intended to receive the serving. The fin 31 has been forced down into the upper end of the cream and thus causes the bar 29 to be held stationary with the serving. With the lower end of the tool held over the 45 receptacle or therewithin, the grip on the piece 11 is released to allow the spring 19 to return the cutter 26 to its normal position nested within the lower end of the housing 10. This action not only causes the cream to be cut away from contact with the housing 10 but also to be cut away 50 from the end piece 27 by the bar 29 so that the serving is permitted to drop freely into the receptacle.

While I have herein shown and described my invention in the one particular form, it is obvious that structural changes may be employed without departing from the spirit of the invention and I, therefore, do not desire to be limited to that precise form beyond the limitations as may be imposed by the following claims.

I claim:

1. The combination of a handle, a cutter extending from the handle, a complementary cutter revolvable circumferentially with respect to the first cutter, a shaft having a spiral groove carried by the handle, said second cutter being revolved by said shaft, a finger piece carried by said handle and movable longitudinally thereof, means interengaging said piece and said shaft to produce rotary motion of the shaft upon movement of said piece toward the handle, and yielding means normally positioning said piece in an outer position to have said shaft retain said second cutter nested with said first cutter.

2. In an ice cream cutter and server, the com-

bination of a handle, a cutter extending from the handle, a complementary cutter revolvable circumferentially with respect to the first cutter, a shaft carried by the handle, said second cutter being revolved by said shaft, a finger piece shiftably carried by said handle, means interengaging said piece and said shaft to produce rotary motion of the shaft upon movement of said piece toward the handle, and yielding means normally positioning said piece in an outer position to have said shaft retain said second cutter nested with said first cutter, a transverse bar rockably carried at the upper end of said cutters, and a fin depending from the bar for insertion into the ice cream.

3. The combination of a handle, a cutter extending from the handle, a complementary cutter revolvable circumferentially with respect to the first cutter, a shaft having a spiral groove carried by the handle, said second cutter being revolved by said shaft, a finger piece carried by said handle and movable longitudinally thereof, means interengaging said piece and said shaft to produce rotary motion of the shaft upon movement of said piece toward the handle, and yielding means normally positioning said piece in an outer position to have said shaft retain said second cutter nested with said first cutter, said first cutter being fixed in relation to said handle, and said second cutter being fixedly carried by said shaft.

4. The combination of a handle, a cutter extending from the handle, a complementary cutter revolvable circumferentially with respect to the first cutter, a shaft having a spiral groove carried by the handle, said second cutter being revolved by said shaft, a finger piece carried by said handle and movable longitudinally thereof, means interengaging said piece and said shaft to produce rotary motion of the shaft upon movement of said piece toward the handle, and yielding means normally positioning said piece in an outer position to have said shaft retain said second cutter nested with said first cutter, said handle being hollowed to receive and guide said piece therein when the handle and piece are squeezed between the hand and fingers of the operator.

5. The combination of a handle, a cutter extending from the handle, a complementary cutter revolvable circumferentially with respect to the first cutter, a shaft having a spiral groove carried by the handle, said second cutter being revolved by said shaft, a finger piece carried by said handle and movable longitudinally thereof, means interengaging said piece and said shaft to produce rotary motion of the shaft upon movement of said piece toward the handle, and yielding means normally positioning said piece in an outer position to have said shaft retain said second cutter nested with said first cutter, said handle being hollowed to receive and guide said piece therein when the handle and piece are squeezed between the hand and fingers of the operator, and a transverse wall across said handle forming a bearing for said shaft and against which said piece is abutted by said positioning means.

6. The combination of a handle, a cutter extending from the handle, a complementary cutter revolvable circumferentially with respect to the first cutter, a shaft having a spiral groove carried by the handle, said second cutter being revolved by said shaft, a finger piece carried by said handle and movable longitudinally thereof,

means interengaging said piece and said shaft to produce rotary motion of the shaft upon movement of said piece toward the handle, and yielding means normally positioning said piece in an outer position to have said shaft retain said second cutter nested with said first cutter, and a transverse terminal plate across the upper end of said second cutter.

5 7. In an ice cream cutter and server, the combination of a handle, a cutter extending from the handle, a complementary cutter revolvable circumferentially with respect to the first cutter, a shaft carried by the handle, said second cutter being revolved by said shaft, a finger piece shiftably carried by said handle, means interengaging said piece and said shaft to produce rotary motion of the shaft upon movement of said piece toward the handle, and yielding means normally positioning said piece in an outer position to have 10 said shaft retain said second cutter nested with said first cutter, and a transverse terminal plate across the upper end of said second cutter, a bar rockably carried under said plate free to swing therearound independently of the second cutter, 15 and a fin downwardly projecting from said bar for insertion into the ice cream, movement of said finger piece causing a travel of said shaft sufficient to produce substantially 180 degrees of travel of said second cutter.

20 8. In an ice cream dipper, a handle, a finger grip piece slidably guided by the handle to enter therein, a foot on the piece within the handle, a member extending transversely across the handle, a shaft rotatably carried by the transverse member screw-threadedly passing through said foot and extending thereabove, an upper shaft bearing carried by the housing to receive the upper end of the shaft, means interengaging the shaft and said bearing to restrain the shaft 25 against longitudinal movement, a spring normally holding said foot against said transverse member, an extension from said handle forming a cutter housing, and a cutter normally nested in said extension, means fixedly connecting the cutter with the lower end of said shaft, whereby said dipper may be operated as a dipper by first 30 inserting it into the ice cream and then by manipulating the handle and finger piece to lift said foot to rotate said shaft and its affixed cutter from its nested position to a position forming a substantially enclosed chamber with said housing extension to retain a serving of ice cream 35 therewithin, and an upper transversely positioned end closure plate on said cutter adjacent said transverse member.

40 9. In an ice cream dipper, a handle, a finger grip piece slidably guided by the handle to enter therein, a foot on the piece within the handle, a member extending transversely across the handle, a shaft rotatably carried by the transverse member screw-threadedly passing through said foot and extending thereabove, an upper shaft bearing carried by the housing to receive the upper end of the shaft, means interengaging the shaft and said bearing to restrain the shaft 45 against longitudinal movement, a spring normally holding said foot against said transverse member, an extension from said handle forming a cutter housing, and a cutter normally nested in said extension, means fixedly connecting the cutter with the lower end of said shaft, whereby said dipper may be operated as a dipper by first 50 inserting it into the ice cream and then by manipulating the handle and finger piece to lift said foot to rotate said shaft and its affixed cutter from its nested position to a position forming a substantially enclosed chamber with said housing extension to retain a serving of ice cream 55 therewithin, and an upper transversely positioned end closure plate on said cutter adjacent said transverse member.

45 10. In an ice cream dipper, a handle, a finger grip piece slidably guided by the handle to enter therein, a foot on the piece within the handle, a member extending transversely across the handle, a shaft rotatably carried by the transverse member screw-threadedly passing through said foot and extending thereabove, an upper shaft bearing carried by the housing to receive the upper end of the shaft, means interengaging the shaft and said bearing to restrain the shaft 60 against longitudinal movement, a spring normally holding said foot against said transverse member, an extension from said handle forming a cutter housing, and a cutter normally nested in said extension, means fixedly connecting the cutter with the lower end of said shaft, whereby said dipper may be operated as a dipper by first 65 inserting it into the ice cream and then by manipulating the handle and finger piece to lift said foot to rotate said shaft and its affixed cutter from its nested position to a position forming a substantially enclosed chamber with said housing extension to retain a serving of ice cream 70 therewithin, and an upper transversely positioned end closure plate on said cutter adjacent said transverse member, a bar, a post on the bar rotatably passing through said cutter end plate to be rotatably carried by said shaft, and a fin extending downwardly from the bar for ice cream engagement.

75 inserting it into the ice cream and then by manipulating the handle and finger piece to lift said foot to rotate said shaft and its affixed cutter from its nested position to a position forming a substantially enclosed chamber with said housing extension to retain a serving of ice cream therewithin, said handle and extension cutter housing forming a continuous unitary piece arcuately curving around from an upper end of the handle to the lower tip of the housing, said housing being substantially a semi-axial hollow conical section, and said cutter being similarly shaped.

80 11. In an ice cream dipper, a handle, a finger grip piece slidably guided by the handle to enter therein, a foot on the piece within the handle, a member extending transversely across the handle, a shaft rotatably carried by the transverse member screw-threadedly passing through said foot and extending thereabove, an upper shaft bearing carried by the housing to receive the upper end of the shaft, means interengaging the shaft and said bearing to restrain the shaft against longitudinal movement, a spring normally holding said foot against said transverse member, an extension from said handle forming a cutter housing, and a cutter normally nested in said extension, means fixedly connecting the cutter with the lower end of said shaft, whereby said dipper may be operated as a dipper by first 85 inserting it into the ice cream and then by manipulating the handle and finger piece to lift said foot to rotate said shaft and its affixed cutter from its nested position to a position forming a substantially enclosed chamber with said housing extension to retain a serving of ice cream 90 therewithin, and an upper transversely positioned end closure plate on said cutter adjacent said transverse member.

95 12. In an ice cream dipper, a handle, a finger grip piece slidably guided by the handle to enter therein, a foot on the piece within the handle, a member extending transversely across the handle, a shaft rotatably carried by the transverse member screw-threadedly passing through said foot and extending thereabove, an upper shaft bearing carried by the housing to receive the upper end of the shaft, means interengaging the shaft and said bearing to restrain the shaft against longitudinal movement, a spring normally holding said foot against said transverse member, an extension from said handle forming a cutter housing, and a cutter normally nested in said extension, means fixedly connecting the cutter with the lower end of said shaft, whereby said dipper may be operated as a dipper by first 100 inserting it into the ice cream and then by manipulating the handle and finger piece to lift said foot to rotate said shaft and its affixed cutter from its nested position to a position forming a substantially enclosed chamber with said housing extension to retain a serving of ice cream 105 therewithin, and an upper transversely positioned end closure plate on said cutter adjacent said transverse member, a bar, a post on the bar rotatably passing through said cutter end plate to be rotatably carried by said shaft, and a fin extending downwardly from the bar for ice cream engagement.
